UNITED STATES PATENT OFFICE.

GEORGE EUGENE MITTINGER, JR., OF NEW CASTLE, PENNSYLVANIA.

APPARATUS FOR MAKING METAL BILGED BARREL-SHELLS.

1,042,946.

Specification of Letters Patent.

Patented Oct. 29, 1912.

Application filed March 9, 1912. Serial No. 682,832.

To all whom it may concern:

Be it known that I, GEORGE E. MITTINGER, Jr., a citizen of the United States, residing at New Castle, in the county of Lawrence 5 and State of Pennsylvania, have invented certain new and useful Improvements in Apparatus for Making Metal Bilged Barrel-Shells, of which the following is a specification, reference being had therein to the accompanying drawing.

My invention relates to improvements in apparatus for making metal bilged barrel shells, and is particularly adapted for forming the shell from a sheet of cold metal.

15 The primary object of this invention is to provide an apparatus by means of which a bilged metal barrel shell can be produced by two operations.

My improved apparatus for forming sheet metal bilged barrel shells, comprises dies used in the first operation that are so shaped that two parallel curved and bilged bends are formed, which contain a curved and bilged area equal to the major portion of 25 the completed shell (preferably about three-fourths) and to form an inverse bend between and extending longitudinally of the two said parallel bends, these dies forming what I term an initial blank.

30 My improved apparatus involves also dies so shaped as to upset the above mentioned inverse bend and give it a curve and bilged shape corresponding to the curve and bilged shape of the finished barrel shell and simultaneously with the shaping of the inverse bend bringing the ends of the parallel bilged bends together, thus completing the barrel shell, ready to have its edges suitably united by lock seaming or otherwise, and 40 ready to receive suitable heads for making the completed barrel.

My present invention pertains only to the forming of what I term an initial blank and then forming this initial blank into what I 45 term a bilged barrel shell. The seaming or uniting of the edges of this barrel shell may be accomplished in any one of several known ways, and the heads may be applied to this shell in any suitable manner without affecting my invention which, as stated, is the forming of a bilged barrel shell.

50 Referring now to the drawings, in which like reference characters designate the same parts—Figure 1 is a perspective view of one form of the dies for forming the initial blank, which is the first step in the forming

of the bilged barrel shell, the sheet of metal to be acted on being shown in dotted lines. Fig. 2 is a perspective of the initial blank. Fig. 3 is a top plan view of the initial blank. Fig. 4 is a perspective view of the dies for practising the second step in forming the bilged barrel shell, the initial blank shown in position in respect thereto. Fig. 5 is a perspective view of the dies for the second 65 step, after they have acted upon the initial blank and showing the bilged barrel shell. Fig. 6 is a perspective view of one of the ends of the male die for the first step and showing a fold distributor which is advantageous in forming all sizes of bilged barrel shells, and essential when forming the ordinary and larger sizes of bilged barrel shells. Fig. 7 is a view taken longitudinally through the center of the dies for forming one of the 70 parallel bends in the sheet of metal, the sheet of metal and dies shown at the beginning of the formation stroke. Fig. 8 is a similar view, the sheet of metal and the dies having reached the position where the dies 75 begin to form the bilges in the two longitudinal bends of the sheet. Fig. 9 is a transverse sectional view taken through the center of Fig. 7. Fig. 10 is an end view of a modified form of male die, which is used in 80 the second step in forming the bilged barrel shell.

The form of dies, shown in Figs. 1, 4 and 5, is such as may be used in forming small 85 bilged barrel shells, or which might be used in forming a larger size barrel, if it is not essential that the ends of the shells be practically free of folds.

In Figs. 6 to 10, I illustrate the preferred 90 type or form of dies by means of which any desired practical size of bilged barrel shell can be produced, with practically smooth ends.

Reference will first be made in the description to Figs. 1 to 5, inclusive, and in which 1 is a female die having two parallel curved die recesses 2 having bilged portions 3, and a central longitudinal projection 4. This projection 4, gradually increases in 100 width from its ends to its center forming an enlarged central portion 5. That portion of each of the recesses 2, approximately lying between the points *a*, *b*, is formed on a curve and bilge to correspond with the curve and bilge of the barrel shell to be produced, while the projection 4 takes that position of the die between *b*, *b*, out of such curve and 105 110

bilge. The male die 6, which coöperates with the die 1, has projections 7 of a shape corresponding to the recesses 2 of the die 1, and a longitudinal groove or recess 8 corresponding in shape to the longitudinal projection 4 of the die 1.

In operation the sheet of metal 9 is placed over the die 1, as shown in dotted lines Fig. 1, and the male die caused to force the sheet into the recesses of the die 1, thus forming what I term an initial blank 10, which corresponds in shape to the shape of the aforesaid dies, as shown in Fig. 2. This initial blank may or may not have the flanges 11 (shown in dotted lines) according to whether the barrel is to have a lock seam; a lap seam or some other form of seam. If the barrel is to have a lock seam, the initial blank will be formed with these flanges 11, which, when the shell is completed, are brought together, as shown in Fig. 5, and these flanges will then be formed into a lock seam in any desired manner, and this seam may be either left on the outside of the shell, or it may be forced through the inner side of the shell, both of said seamings being old and well-known to those skilled in this art and need not be illustrated or further described.

30 Referring now to the initial blank in Fig. 2, 2' indicates the parallel curved bends; 3' the bilged portions; 4' the recess or groove formed by the inverse bend; and 5' indicates the central widened portion of the inverse bend, which gradually widens from its ends to the center thereof. This initial blank, like the die recesses 2 of the die 1, has that portion between the parts a', b', formed on a curve and a bilge corresponding to the 40 curve and bilge of the bilged barrel shell or the barrel, while that portion between b', b', is not of the same shape, but is in the form of an inverse bend.

Thus far I have described the first operation in forming the bilged barrel shell, and the second step which completes the bilged barrel shell will now be explained.

Referring particularly to Fig. 4, 12 is a female die, which has a curved and bilged 50 recess of a shape corresponding to the curve and bilge of the barrel shell to be produced and is preferably approximately of an area corresponding to about half the external area of the completed barrel shell. In effecting this second step, the initial blank 10 is placed on the die 12 with the inverse bend 4' directly over the center of the die, and a male die 14 engages the top of this inverse bend 4', as illustrated in Fig. 4. For the 60 purpose of centralizing the initial blank over the die 12 and causing it to properly enter the die as it is forced therein by the male die 14, I provide a positioning member 20, which is a bar. This bar has attached thereto supporting and guiding rods 21 that move down-

ward through the die 12 against the tension of springs, and this bar is of a shape to fit in a longitudinal recess 23, formed in the bottom of the die recess 13. The upper surface (not shown) of this bar is of such shape 70 that when the bar is in the recess 23, it corresponds with and completes the curved and bilged shape of the recess 13 and leaves the surface unbroken. As the male die 14 descends, it carries the inverse bend 4' down into the die recess 13 and forms it into a curved and bilged shape, corresponding to the bilge and curve of the completed barrel shell, and this action simultaneously brings the outer edges of the parallel bends 2' together, as shown in Fig. 5, thus completing the second operation of the bilged barrel shell.

When forming a full size and larger barrel with this apparatus, and when the dies 1 and 6 have reached to the point shown in Fig. 8, so that the bilge of the die 6 is in a plane with the ends 25 of the recess 2 of the die 1, and as the die 6 continues downward to form the bilge in the sheet, there is a 85 tendency to the forming of folds in the metal at the ends of the dies. As the male die moves downward, the edges of the sheet are drawn inward to furnish the additional metal required for the bilge and this provides a surplus amount of metal at the ends of the molds and sheet and this surplus metal, in practice, is found to form into two decided folds, which is objectionable in a 90 barrel and, in some instances, this fold will double over and make four thicknesses of metal, which will prevent the male die from moving down into the female die the required distance to form the proper bilge in the sheet. I have discovered that this excess 100 metal at the ends of the sheet and the mold can be so uniformly distributed throughout the end of the bends in the sheet that it is made manifest only in slightly perceptible 105 and entirely unobjectionable waves, which 110 will not interfere in any manner with the tight fitting of heads in the barrel and otherwise completing it into a perfect bilged barrel. This uniform distribution of the metal at the ends of the bends, I accomplish by 115 what I term metal fold distributors carried by and forming a part of the dies. These metal fold distributors may be carried by either the male or female die, but, as here shown, they are carried by the male die as 120 illustrated at 26. These metal fold distributors are, in fact, advance receding end portions of the dies. They consist in making the ends 26 of the projections 7, separate and capable of a movement independent of the 125 die proper a distance equal to the bilge of the die. These metal fold distributors 26 are normally spring projected in advance of the die proper, as just stated, a distance equal to the depth of the bilge to be formed and they 130

are held projected by suitable strong and preferably adjustable springs 27. Referring now to Figs. 7 and 8, it will be noted that these metal fold distributors 26 are in advance of the ends of the molds and are in a plane with the bilge 3² of the male die, and as shown in Fig. 7, they serve an additional function of engaging the edges of the sheet 9 at the same time that the bilge 3² engages the metal which insures the sheet being carried downward uniformly throughout its width into the recesses 2 of the die 1, until the edges of the metal 9 engage the ends 25 of the recesses 2. At this point the metal fold distributors 26 begin to perform their functions of taking care of the excess metal and disturbing the tendency to fold uniformly throughout the bends of the sheet. When the dies have reached the point indicated in Fig. 8, further movement thereof begins to form the bilge and additional metal is required and is drawn inward from the edges of the sheet and, as above stated, this causes the excess of metal at the ends of the sheet. I have discovered in practice that these members 26 which, for convenience of reference, I aptly term metal fold distributors, perfectly take care of the excess metal and uniformly distribute it throughout the 30 bend and to some extent, compact or contract the metal at this point, while at the same time permitting the engaged edges of the metal to slip thereby sufficiently to assist in providing the additional metal required for 35 forming the bilge of the sheet. The edges of the sheet are drawn inward to provide the additional metal for the circumference of the bilge, while the ends will move or slide under the fold distributors 26 sufficiently to 40 provide the additional metal required by the longitudinal formation of the bilge. I am inclined to believe that this movement of the metal under the fold distributors 26, assists in uniformly distributing, smoothing out 45 and preventing any objectionable waves or folds in the edges or ends of the bends in the blank. It will be understood, of course, that after the dies have reached the point indicated in Fig. 8, the die 6 moves inward independent of the fold distributors, the fold distributors being in effect the receding portions of the die 6.

It is necessary that the dies for the second step be provided with fold distributors for 55 the same reasons that the dies of the first step are provided with such members. In Fig. 10 is illustrated the receding folding distributors 28 of the die 14, and these folding distributors are normally projected by 60 strong springs 29. They act and perform their function in the same manner as explained in respect to the fold distributors 26, which has already been fully described.

By reference to Figs. 1 and 2, it will be 65 seen that the top of the projection 5, of the

female die 1, is in a plane below the outer edges of the recess 2, when the projection 5 is made rigid with the die. By reason of this fact, the sheet of metal 9 when placed in position to be formed is not in engagement with the projection when the male die 6 begins to form the initial blank. When the die 6 begins to descend and the sheet of metal is being carried into the recesses 2, the edges of the sheet metal are drawn inward and in order to form a perfect blank, it must move equally from both edges. To effect this result, I make the upper portion 29' of the projection 5 movable and hold it projected by strong springs 30, so that its 70 top is in a plane with the outer edges 31 of the recesses 2. This causes a central friction between the sheet and the projection 29' and, in practice, will cause the sheet to move inward uniformly and equally from both 75 edges. When the die 6 has reached the full limit of its movement, the movable top 29' of the projection 5, will be forced down and its top will be in a plane below the plane of 80 the outer edges 31 of the recesses 2. 90

Referring now to Figs. 4 and 5, it will be noted that the male die 14 is provided with a pressure beam 17 and that one leg 18 of this pressure beam is hinged so that it would swing outward. The object of this is to permit the removal of the completed bilge barrel shell 16. The lower end of the swinging leg 18 is preferably held in position by any suitable form of latch 32. 95

The springs which project the fold distributors are made sufficiently strong to hold them projected against the sheet of metal as the male die enters the female die, and are thus sufficiently strong to bend the metal to the shape of the fold distributors and these 100 distributors combine with the end curves of the female die recesses to shape the metal corresponding to the shape of the ends of the said mold recesses and the fold distributors. 105

Having thus described my invention, what I claim and desire to secure by Letters Patent is:

1. In mechanism for making bilged barrel shells, the combination with means for forming a sheet metal blank having two parallel approximately semi-circular bends having bilged portions between their ends and a central longitudinal projection widened from its ends to its center, of means for 115 upsetting the said projection and shaping it into a bilge corresponding with the bilge of said parallel bends. 120

2. An apparatus for forming initial blanks for bilged barrel shells, comprising a 125 female die having parallel curved die recesses having their bottoms and outer sides curved and bilged to correspond with the curve and bilge of the barrel shell and a central projection, to form an initial blank 130

adapted to have its central inverse bend upset and bilged to correspond to the bilge of the completed barrel shell.

3. In an apparatus of the character described, a female die having a recess with a central bilged portion forming a relatively small curved end, one of said dies having projected receding fold distributers at its ends for the purpose described.

10 4. In an apparatus of the character described, a female die having two parallel die recesses each having a central bilged portion forming relatively small curved ends, a male die having two bilged projections shaped to co-act with the said female die, one of said dies having at each end projected receding fold distributers for the purpose described.

20 5. In an apparatus of the character described, a female die having a die recess with a bilged central portion forming relatively small curved ends, a male die shaped to co-act therewith, one of said dies having projected receding metal fold distributers 25 at its ends, said distributers having a shape corresponding to the shape of the ends of the mold recess with which they co-act.

6. In an apparatus of the character described, a female die having a mold recess 30 with the bilged central portion forming relatively small curved ends, a male die having a bilged portion to co-act with the said female die, the male die having projected receding ends shaped to co-act with the ends 35 of the female die to form fold distributers as described.

7. In an apparatus of the character described, a female die having parallel curved bilged recesses and a central longitudinally 40 extending projection, the said projection having a receding top normally projected in a plane with the outer edges of the said parallel recesses, for the purpose described.

8. In an apparatus of the character described, the combination of a female die 45 having parallel curved bilged recesses and a longitudinally central projection, said pro-

jection having a receding end projected in the plane of the outer edges of said die recesses, a male die shaped to co-act with the 50 female die, one of said dies having projected receding fold distributers for the purpose described.

9. An apparatus for forming an initial sheet metal blank for barrel shells, including a female die having two parallel recesses, said recesses having their bottoms and outer sides curved and bilged to correspond with the curve and bilge of the completed barrel shell, and a central projection 60 gradually widened from its ends to its center, and an initial male die shaped to co-act with the female die to form an initial blank corresponding to the shape of said dies, whereby said blank is adapted to be formed 65 into a completed bilged barrel shell.

10. In an apparatus for the purpose described, a female die having a curved and bilged recess forming reduced curved ends, a male die of a shape to co-act therewith, 70 one of said dies carrying metal fold distributers co-acting with the reduced end portions to distribute the metal and prevent the formation of folds therein as the metal is pressed into the bilge of the female die. 75

11. In an apparatus for the purpose described, a female die having two parallel recesses, said recesses having their bottoms and outer sides curved and bilged to correspond with the curve and bilge of the completed barrel shell, and a central projection shaped to cause the sheet metal blank to have more metal at the center of the projection formed therein in the blank, and a male die shaped to fit into the female die to form 80 a blank adapted to be converted into a bilged barrel shell by upsetting and bilging the central projection of the blank.

In testimony whereof I hereunto affix my signature in the presence of two witnesses.
